MEANS FOR APPLYING MECHANICALLY THIN METALLIC SHEETS TO VARIOUS SURFACES

Henry Rose, Haddonfield, N. J.

Application July 5, 1934, Serial No. 733,797

4 Claims. (Cl. 271—18)

This invention has to do with the art of mechanically applying thin metallic sheets or foils to various surfaces.

In its preferred embodiment the invention is a device and a method for applying thin sheets of metal to sundry materials like leather, fabrics, wooden and metallic surfaces of various kinds, etc., to which it is desired to have adhered different kinds of thin metallic strips for decorative or other purposes. While the invention includes the instrumentalities above mentioned, I wish it to be understood that I consider the aforesaid means not only combinatively novel, but in so far as I am advised, certain of the elements going to make up such means are new in less combinations than the whole, and some capable of individual use, as will more clearly appear hereinafter.

To explain fully the advantages of my invention I shall refer briefly to the operation of the well-known type of device adapted to applying a metallic foil like silver leaf to the surface of a material like leather. Such a device consists of a frame of wood or any suitable material covered on one side with a material of fine mesh—usually silk, gauze or organdie. To the other surface and to one side of the fine-meshed material is applied an oily or somewhat adhesive preparation. The frame is then pressed with the oiled surface of the gauze outward against the silver or otherwise metallic leaf. With a deft movement of the hand, which requires an untrained operator three or four weeks to acquire because of the extremely fragile and sensitive nature of the metallic sheet, the frame and the adhering metallic leaf are transferred to the surface of the material which has been freshly covered with an adhesive substance and by touching the inner surface of the gauze of the frame with a finger the metallic leaf is deposited in the desired place on the material to be thus covered. Such a device and method often result in a non-uniform application of the metallic strips, in their occasional creasing and tearing and not infrequently in the deposition of spots and streaks of the oily substance on the strips thus applied.

With the foregoing in view, my invention provides a means and a method for applying the metallic strips or sheets in a strictly uniform manner, for avoiding the creasing and the tearing of the strips incident to the employment of the old method and for eliminating entirely the oily spots and streaks that may develop because of the use of an adhesive substance applied to the gauze of the frame.

Supplementing these advantages are the out-

standing ease and facility with which an untrained operator can almost immediately apply the metallic strips to any properly prepared surface with consistent uniformity and neatness.

As before premised, means for the last named purposes have been devised and combined with the other instrumentalities of this invention, all of which will be now described in detail on reference to the accompanying drawing, in which:

Figure 1 is a plan view of the metallic sheet applying device resting upon a metallic leaf filed within a book of such leaves.

Figure 2 is a plan view of the aforementioned device holding to itself a metallic leaf to be applied to the surface of a material.

Figure 3 is an enlarged cross sectional view taken vertically on the line 3—3 of Figure 1.

Figure 4 is an enlarged cross sectional view taken vertically on the line 4—4 of Figure 2.

Figure 5 is a plan view of a modified form of the metallic sheet applying device.

Figure 6 is a plan view of the material to be coated of which part has been covered with metallic strips.

Referring to the drawing in which like reference characters indicate like parts, 1 represents a frame constructed of wood or any other suitable material, one side of which is covered with a bottom 2 consisting of a transparent, non-conducting material like bakelite, glass, celluloid, etc. The central portion of the bottom 2 is cut away and replaced by the screen 3 constructed of any finely meshed material, preferably metallic in nature, although ordinary gauze has been effective in operation. The metallic clip spring 4 is rigidly attached to the two sides of the frame 1 and to the lower side of the spring 4 are fastened the two blocks 5 and 5' for the purpose of arresting too pronounced a downward movement of the spring 4 when it is depressed at the block 6 which is rigidly attached by any suitable means to the spring 4 and is constructed of any material, preferably metallic in nature, although other materials have been successfully employed in operation. The spirit level 7 is mounted on one side of the frame 1 and enables the operator to hold the device in a horizontal plane when the metallic leaf 8 is to be applied to the material 9. Two or more set screws 10 and 10' are attached to the lower part of one of the sides of the frame 1 for the purpose of enabling the operator to rest the device on the material 9 that is to be covered with the metallic leaves 8 and at the same time of preventing him, when the device has been adjusted to a hori-

zontal plane by means of the level 7, from scuffing or otherwise disarranging the metallic leaves already deposited.

The manner in which my device can be utilized becomes obvious when the operation is more fully described. The transparent non-conducting bottom 2 is rubbed either with the hand or with a cloth of such a material as to produce in it a state of electrification. As illustrative of the electrified condition of the bottom 2—when it is constructed of glass, a cloth of silk moved briskly over its surface sets up a positive electrification in the bottom 2. When the device is then pressed gently upon the leaf 8 of silver, gold or any other metallic substance, the leaf is immediately attracted to the bottom 2 and lies in a smooth, unwrinkled expanse over its surface. The device is then carried to the material 9 which is to be covered with the metallic strips. Such a movement is most easily executed in spite of the extremely fragile nature of the metallic leaf. If the material 9, for example leather, has been covered with a suitable adhesive substance then the operator whether he is skilled or inexperienced merely presses the block 6 against the screen 3 after the device has been correctly placed over the area of the material 9. The contact of the metallic sheet 8 with the moist leather 9 and of the operator's finger with the block 6 causes a discharge of the electrification residing on the bottom 2. This resulting discharge of the electrification induces the metallic strip 8 to fall into the desired section on the material 9. After the material 9 has become partly covered with the metallic coating as shown in Figure 6, the operator in working from the left toward the right rests the set screws 10 and 10' of the frame on the leather or other material and, guided by the level 7, adjusts the device to a horizontal plane before the block 6 is pressed to discharge a metallic leaf. In this way leaf after leaf of the thin metal can be quickly, uniformly and neatly deposited without in any manner disturbing leaves already laid or without causing the loss of leaves incident to the use of the old method when air currents and inexperience on the part of the operator proved costly.

In Figure 5 is shown a modified form of my invention. The frame 1' is covered with the gauze 2' except for the portion at one end which is covered with a transparent and non-conducting substance 3'. In all other respects the modified form is similar to the preferred type already described with the exception of the centrally placed screen 3 as shown in Figures 1, 2, 3 and 4. The modified device is designed to pick up the metallic leaf 8' along the edge 9' in a manner similar

to that explained for the preferred form. Although the use of oil or glycerine is obviated, yet the operator must acquire the difficult technique of "flipping" the device through the air before he deposits the leaf 8', intact and unwrinkled, upon the desired place on the leather 9.

While the constructions as shown and described are the preferred embodiment of my device, nevertheless the same may be modified in detail without departing from the spirit and the scope of the invention as defined in the annexed claims.

Having thus described my invention, I claim as new and desire to secure by Letters Patent:

1. A device for applying mechanically thin metallic sheets comprising in combination a frame, a transparent and nonconducting medium attached to the under side of said frame, a screen covering a cut out section of said medium and a means for releasing a metallic sheet from said medium.

2. A device for applying mechanically thin metallic sheets comprising in combination a frame, a screen attached to the under side of said frame, a transparent and nonconducting medium attached to and covering a portion of said screen and a means for releasing a metallic sheet from said medium.

3. A device for applying mechanically thin metallic sheets comprising in combination a frame, a transparent and nonconducting medium attached to the under side of said frame, a screen covering a cut out section of said medium, a spring clip secured rigidly to the sides of said frame, a block positioned intermediate the ends of said spring clip and adapted to make contact with said screen for the release of a metallic sheet, a level attached to a side of said frame and adapted to determine the horizontality of said frame, and set screws attached to a side of said frame and adapted to hold said frame in a horizontal plane.

4. A device for applying mechanically thin metallic sheets comprising in combination a frame, a screen attached to the under side of said frame, a transparent and nonconducting medium attached to and covering a portion of said screen, a spring clip secured rigidly to the sides of said frame, a block positioned intermediate the ends of said spring clip and adapted to make contact with said screen for the release of a metallic sheet, a level attached to a side of said frame and adapted to determine the horizontality of said frame, and set screws attached to a side of said frame and adapted to hold said frame in a horizontal plane.

HENRY ROSE.
